UNITED STATES PATENT OFFICE.

HOWELL W. SOUDER, OF TAMAQUA, PENNSYLVANIA, ASSIGNOR OF ONE-HALF TO W. D. ZEHNER, OF LANSFORD, PENNSYLVANIA.

SEMAPHORE-OPERATING DEVICE.

SPECIFICATION forming part of Letters Patent No. 735,420, dated August 4, 1903.

Application filed September 25, 1902. Serial No. 124,798. (No model.)

To all whom it may concern:

Be it known that I, HOWELL W. SOUDER, a citizen of the United States of America, and a resident of Tamaqua, Schuylkill county,

5 State of Pennsylvania, have invented certain new and useful Improvements in Semaphore-Operating Devices, of which the following is a specification.

My invention relates in general to means 10 for moving a vibrating or reciprocating member back and forth along its predetermined path and automatically locking it in its various positions. The specific application herein shown consists of a vibrating signal or 15 semaphore and means embodying my invention for moving the semaphore-arm and locking it in both its raised and lowered positions. Certain features of my invention, including the yielding connection for operating the reciprocating element, make it peculiarly adaptable to electrically-operated mechanism.

In the case of a semaphore which is exposed to the wind and storms the strain of 20 sustaining it in an elevated position is frequently too much for an operating mechanism which may, however, have ample power for lifting it initially to such position. On the other hand, when an electromagnet is used for elevating the semaphore-arm the 25 mechanism is free and uncontrolled when the semaphore-arm is down, and strong gusts of wind may swing the arm to and fro, rapidly wearing out and possibly disarranging the entire apparatus. Either or both of these 30 difficulties is avoided by the use of my invention. Moreover, in signals or other apparatus operated by the direct pull of a magnet the greatest resistance is encountered at the beginning of motion, when the inertia of 35 the parts and the greatest friction has to be overcome. At such time also the pull of the magnet is weakest, as the armature is farthest removed from it. Thus a magnet of unnecessarily large size is required and waste of 40 power results. The yielding connection between the operating parts and the semaphore-arm, which is an essential element of my invention, remedies this difficulty by reducing the initial pull necessary and concentrating 45 the work toward the end of the stroke, when the pull of the magnet is greatest.

The best form of apparatus at present known to me embodying my invention is illustrated in the accompanying two sheets of drawings, in which—

55

Figure 1 shows a semaphore with a solenoid for operating same, the parts being in a condition of rest with the semaphore-arm down. Fig. 2 is a detail of the same after the mechanism has operated far enough to 60 unlock the semaphore-arm. Fig. 3 is a detail of the same with the semaphore-arm up and locked in that position. Fig. 4 shows the same after the semaphore-arm has been unlocked and is ready to fall, and Fig. 5 is a 65 detail of a modification.

Throughout the drawings like reference figures indicate like parts.

1 represents the supporting-post of a semaphore-signal, to which is pivoted the semaphore-arm 2 by the short shaft or pivot 3. The semaphore-arm has a short crank 4 for operating the same, and to this is connected the spring or other yielding element 5, the other end of said spring being connected to 70 a rod or other tension member 6. To the lower end of the rod 6 is connected, either directly or intermediately, the core 7 of a solenoid 8 or other electromagnetic apparatus, which is excited by the current passing 75 through the circuit having the terminals 9 and 10 when the same is closed by means of a switch 11 or other similar means. To the operating member 6 is attached a slide 12 by means of the lug 13. This slide has a slot 80 14, which enables it to move up and down on the shaft 3 as a guide. At the lower end of the slide 12 is a sliding locking-bolt 15, normally pushed upward by the spiral spring 16, and at the upper end of the slide is similar 85 locking-bolt 17, normally pushed downward by a spiral spring 18, these parts being arranged with reference to the slot 14 in substantially the manner shown in the drawings. On the shaft 3 or otherwise connected to the 90 hub of the semaphore-arm 2, so as to move therewith, is the disk or hub 19, provided with notches 20 and 21, so shaped as to cooperate with the locking-bolts 15 and 17.

In the modification shown in Fig. 5 the above-described mechanism, with the exception of the semaphore-arm, is shifted to a

lower position on the post 1, and the crank-arm 4 is connected, by means of a link 6^a, to the crank-arm 4^a of the semaphore, which vibrates on a stud-shaft 3^a. In this manner 5 the projection of the slide 12 above the end of the semaphore-post is obviated.

The mode of operation of my invention is as follows: Assuming the parts to be in the position shown in Fig. 1 and the switch 11 10 to be closed or the solenoid 8 otherwise energized, the initial pull on the core 7 will be transmitted through the rod 6 or other operating means to the reciprocating double-acting slide 12 and also to the lower end of the 15 spring 5. The semaphore-arm being locked in the position shown, by reason of the fact that the locking-bolt 15 engages the notch 20 there can be no movement of the crank-arm 4. The effect of the pull of the rod 6 will 20 therefore be to simultaneously stretch the spring 5 and move the slide 12 until the parts assume the position shown in Fig. 2. This having withdrawn the locking-bolt 15 from the notch 20, the contraction of the spring 5 25 and further movement of the rod 6 will pull the semaphore-arm up into the position shown in Fig. 3. The slide 12 will continue to move downward during this operation, and as the end of the stroke is approached the locking- 30 bolt 17 will strike the hub 19. This will arrest the movement of the locking-bolt 17, and as the slide 12 will continue to move the spring 18 will 35 be compressed. When the semaphore-arm has reached the position shown in Fig. 3—that 40 is to say, its position of elevation—the notch 21 of the hub 19 will come opposite the locking-bolt 17, which will be forced into engagement with the same by the expansion of the spring 18, thus locking the semaphore-arm in 45 its elevated position, all as shown in Fig. 3. When the circuit through the solenoid 8 is broken and the same becomes dead, the pull upon the core 7 and rod 6 will no longer exist. The initial action resulting from this release of pull will evidently be the contraction 50 of the spring 5, which has been expanded, as shown in Fig. 3, by the final portion of the downward movement of the rod 6. This contraction of the spring 5 will lift the double- 55 acting slide 12 into the position shown in Fig. 4, withdrawing the locking-bolt 17 from the notch 21, and so leaving the semaphore-arm free to fall back to its lowermost position by gravity, thereby throwing all the parts into the position shown in Fig. 1 in readiness for a second operation.

The advantages of my invention comprise the positive locking of the semaphore-arm in both positions and the automatic unlocking 60 thereof by the operating means itself, thereby avoiding complication and multiplication of mechanism. A further advantage consists in the reduction of the initial pull necessary to be exercised by the magnet in that the first 65 effect of the motion of the parts is merely to expand the spring 5, which presents a gradually-increasing resistance which may begin

at zero. It is evident that by properly proportioning the parts the contraction and expansion of the spring 5 might do the whole 70 work of swinging the semaphore-arm—that is to say, the motion of the solenoid-core 7 or magnet-armature would simply do the gradually-increasing work of expanding spring 5, which in contracting would do the work of 75 swinging up the semaphore-arm.

While I have illustrated my invention as applied to the work of swinging a semaphore-arm and locking the same, it is evident that it might be applied to many other purposes 80 in which an element is to be moved back and forth along a predetermined path and locked automatically in one or more of its extreme positions. Such modified applications of the mechanism would still be within the scope of 85 my invention if the essential feature of the spring connection or the combination of the spring connection with an operating connection for both the locking device and the moving element were retained. It is further evident that the spring 16 might be dispensed with and the relative motion of the bolt 15 90 with reference to the slide 12 thereby eliminated, the yielding action of the spring 5 being sufficient to secure the easy engagement 95 of the bolt 15 with the notch 20 when the semaphore falls into the position shown in Figs. 1 and 2.

Having described my invention, what I claim as new, and desire to protect by Letters 100 Patent, is—

1. The combination of an element capable of movement back and forth along a predetermined path, mechanism for locking said element in one of its extreme positions, an 105 operating member, a connection from said operating member to said locking mechanism, and a simultaneously-acting elastic connection from the operating member to the moving member separate from and independent 110 of the above-mentioned connection to the locking mechanism.

2. The combination of a supporting-frame, a vibrating arm journaled therein, a locking device for said arm, an operating member, a 115 connection from said operating member to said locking device, and a simultaneously-acting elastic connection from the operating member to the vibrating arm separate from and independent of the above-mentioned connection to the locking device.

3. The combination of a supporting-frame, a vibrating arm journaled therein having a hub provided with notches corresponding to the various positions of the arm, a reciprocating double-acting locking-slide adapted to alternately engage said notches, a connection for vibrating the arm, means controlled by said connection for reciprocating the locking-slide, and a yielding attachment for the 125 operating connection to the vibrating arm.

4. The combination of the supporting-post and semaphore-arm journaled therein, the hub of said arm being provided with notches

corresponding to the two signaling positions of said semaphore-arm, a reciprocating locking-slide provided with yielding projections alternately engaging said notches, a semaphore-operating connection to which said locking-slide is attached, and a spring interposed in the said operating connection between the point of the locking-slide attachment and the semaphore-arm.

5. The combination of the supporting-post and semaphore-arm journaled therein, the hub of said arm being provided with notches corresponding to the two signaling positions of said semaphore-arm, a reciprocating locking-slide provided with yielding projections

alternately engaging said notches, means for operating said reciprocating slide and a spring connection between said means and the semaphore-arm.

6. The combination of a movable signal, an ²⁰ electromagnet, a movable armature for said magnet and a spring connection between said armature and movable signal.

Signed at Lansford, Pennsylvania, this 15th day of September, 1902.

HOWELL W. SOUDER.
